UNITED STATES PATENT OFFICE.

CANUTE H. MICKESEN, OF BENCH, IDAHO.

HAY-STACKER.

1,175,792.

Specification of Letters Patent. Patented Mar. 14, 1916.

Application filed June 7, 1911. Serial No. 631,736.

To all whom it may concern:

Be it known that I, CANUTE H. MICKESEN, a citizen of the United States, residing at Bench, in the county of Bannock and State of Idaho, have invented certain new and useful Improvements in Hay-Stackers, of which the following is a specification.

My invention relates to hay stackers, and more especially to power-operated hay stackers, and the object of my invention is to provide means whereby the load of hay which is lifted by the elevator table may be deposited in any suitable place to be found upon the stack.

The invention consists of a base-frame upon which is rotatably mounted an upright suitably supported laterally by braces secured at their lower ends to the base frame and at their upper ends to a cap-piece forming a bearing for the rotatable upright. Booms are pivotally attached to the upright above the braces and at their outer ends there is an elevator table pivotally connected therewith. It projects beyond its pivotal connection with the booms, and a stay rod is connected thereto by a link connection and by a link connection with the upright. A hoisting mechanism is connected with the movable parts of the derrick.

The objects of the invention are to provide a mechanism that will elevate the fork to a higher plane and to provide for a better transmission of power to raise the booms; to improve the construction of the booms whereby their strength and rigidity are increased; to provide improved means for controlling the elevator table; to provide means for tripping the elevator to discharge the load; and to provide means for locking the upright in position when the elevator is receiving and elevating the load.

With these and other objects in view the invention presents a novel combination and arrangement of parts as described herein, 45 pointed out in the claims, and as illustrated by the drawings, wherein:—

Figure 1 is a side view of my invention, the elevator being in a lowered position. Fig. 2 is a somewhat similar view to that shown in Fig. 1, the table, however, being elevated. Fig. 3 is a front view of my invention, the table being in a lowered position. Fig. 4 is a side elevation of the upright showing the manner of locking. Fig. 5 is a front view of the locking means. Fig. 6 is an enlarged plan view of the elevator

table. Fig. 7 is an enlarged detail back view of the elevator table.

Referring now to the drawings for a more particular description: Figs. 1, 2 and 3 indicate a hay stacker which may be provided with any suitable base 3 so that the revolving upright 5 may be sustained, substantially in a vertical position. Upon the cross tie 2 of the base 3 is placed a bearing 32 for the purpose of receiving the lower end of the upright 5. The upright 5 is braced laterally by the braces 4, secured at their lower ends to the base 3 and at their upper ends to the cap 37. The top 38 and 60 the bottom 39 of the cap 37 are firmly secured to the upright 5. Roller bearings 52 are placed between the top 39 and the bottom 38 of the cap 37. The said roller bearings are held in place by the bolts 53. By 65 the revolving of the upright 5, the roller bearings 52 revolve around the inner face of the cap 37. Near the center of the upright 5 are firmly secured two collars 12. One of the collars is for supporting the 70 booms 16, while the other one is for supporting the stay rods 31. Between the collars 12 and firmly secured to the upright 5 is a bracket 13 for the purpose of securing the locking device shown 75 enlarged in Figs. 4 and 5. Near the upper end of the upright 5 and placed within the upright is a roller 16' over which passes the rope 11. Upon the top of the upright 5 is placed a cap 9 for the purpose of securing the guy ropes 10. Between the collars 80 12 and the roller 16' and fulcrumed to the upright 5 is a tilting beam 6. A casting 8 is firmly secured to the upper end of the tilting beam 6 for the purpose of supporting the double tree B. A hole is cut near the lower end of the tilting beam 6 for the purpose of allowing the rope 11 to pass through. An eye bolt 35 is secured through the lower end of the tilting beam 6, to which 85 is attached a pulley 26. The booms 16 are secured to the collars 12 by lugs 7' and to the elevator table A by means of the bracket 45. The stay rods 31 are secured to the lugs 7 on the collar by means of links 30, and to the hook 29 on the back of the elevator A by means of links 30'. The hooks 29 are firmly secured to the vertical brace 17 of the elevator table A. The vertical braces are firmly secured together by means of 90 horizontal braces 18. Secured to the back 95 of the vertical braces 17 is a housing 19

for covering the spring catch 23. The spring catch 23 is for the purpose of securing and locking the elevator table 21 in a horizontal position by hooking over the catch 20 which is firmly secured by means of lugs 20' to the cross tie 50 of the elevator table. The cross shaft 22 is secured to the elevator brackets 45, on which when tipping to unload the hay, the elevator table 10 revolves. A spring 48 is placed around the shaft 22. One end of the spring 48 is secured at 51 to the elevator brackets 45; the other end is secured into plate 49 of the elevator table. The tripping lever 40, 15 hinged to the locking spring 23, at 46, has a projecting arm 47 to which a rope is fastened.

The locking device, shown enlarged in Figs. 4 and 5, is secured to the upright 5 by 20 means of a bracket 13 through which passes the rod 14. In the upper ends of the booms 16 is a lifting plate 15 pivotally secured. A hole is cut in the lifting plate 15 through which passes the lower end of the rod 14. 25 The holes 44 in the rod 14 are for the purpose of placing a bolt 43 for regulating the lift of the booms. The rod 14 is shown down with its lower end locked within the groove 42 of the cap 37. The lugs 43 on the cap 37 30 are for the purpose of receiving the upper ends of the braces 4. The pulleys 24, 25, 26, and 27 are to receive the power rope 28.

In the operation of my invention, I employ a power rope 28; said rope is secured to 35 the tilting beam 6, at 34, thence brought down and under pulleys 24, thence up over pulleys 25, thence over pulley 26, and then down under pulley 27, then out to the power. By power being applied to the rope 28, the 40 booms 16 to which elevator A is attached, are elevated to the required height by the draft upon the rope 28. By elevating the said booms 16, the lever lifting device 15 in the upper end of said booms 16 is also ele- 45 vated to come in contact with the bolt 43' in the rod 14, thereby lifting said rod out of the notch 42 in the flange of the cap 37, thus allowing the elevator A to swing over the stack, by the turning of the upright 5. As 50 soon as the elevator has reached the desired spot over the stack, the operator pulls on the trip rope 56, thus causing the elevator table to trip and discharge the load. As soon as the load is off the table 21, the 55 springs 48 turn the table back to its normal position. The dotted lines in Fig. 2 show the table tipped. I operate the tilting beam in the following manner: Rope 11 is secured to the bracket 8, then passes through the up- 60 right and over the roller 16', passed loosely down through a hole in the lower end of said tilting beam 6, thence through an eye bolt 36 secured in the upright 5 to within easy reach of the operator and secured around a 65 hitching cleat at any convenient place on the

main mast or stays. The rope 11 is used for raising and lowering the tilting beam 6, thus regulating the height of the lift for the elevator; the rope 11 is also tied through the eye bolt 36 and is within easy reach of 70 the operator.

Having thus described my invention what I claim and desire to secure by Letters Patent, is:—

1. In a haystacker, in combination, suitable lifting means comprising an upright, lifting booms, an elevator table, and a locking device comprising a locking rod, a collar within which the upright revolves, a cap mounted on the collar having a notch therein through which the locking rod normally passes, and coöperating means carried by the rod and the booms to release the rod from the notch at a predetermined time. 75

2. In a hay stacker, in combination, suitable lifting means, comprising an upright, lifting booms, an elevator table, and means for elevating the table; and a locking device comprising a locking rod, a lifting plate pivotally secured between the inner ends of the lifting booms adapted to lift the locking rod, a collar within which the upright revolves, and a cap mounted on the collar, the cap having a notch therein through which the locking rod normally passes. 85

3. In a hay stacker the combination of a supporting base, a revolving upright mounted upon the supporting base, a loading elevator, a pair of lifting booms, a lifting plate, said lifting booms being pivotally mounted 100 upon the upright, said loading elevator being pivotally mounted on the said booms, locking means adjustably secured to the side of said upright adapted to retain the elevator in position to receive and elevate the 105 load, said locking means comprising a bracket mounted on the upright, a lifting plate pivotally secured between the inner ends of the booms, a vertical rod passing through the said lifting plate and the said 110 bracket, a series of holes in the said locking rod and a bolt passing through one of said holes adapted by being inserted in a higher or lower hole to adjust the point of elevation at which the elevator swings. 115

4. In a hay stacker the combination of a supporting base, a revolving upright, a tilting beam pivotally secured to the said upright, a loading elevator, a pair of lifting booms mounted upon the upright, a pair of 120 fixed collars surrounding the upright, said tilting beam being fulcrumed to the said upright and adapted to regulate the lift of the booms, a double-tree pivotally supported at the upper end of the said tilting beam, 125 a pair of pulleys secured to the ends of the said double-tree by eye-bolts, a pair of pulleys secured to the rear ends of the said booms by means of eye bolts, a power rope connected at one end to the tilting beam, 130

passing through the said pulleys in turn and thence through a pulley on the inner end of the tilting beam and thence through a pulley attached to the base and adapted to 5 raise and lower the elevator.

5. In combination a hay stacker comprising a supporting base, a mast rotatably mounted upon the base, a roller bearing collar within which the mast rotates, lateral 10 braces having their bottom end secured to the base and their upper end secured to said collars, a pair of fixed collars mounted on the mast above the roller bearing collar, a tilting beam fulcrumed on the mast above 15 the collars, a clamp fixed to the upper end of the tilting beam, a rope attached to the upper side of said clamp, a slot in the top of said mast, a pulley in the said slot, a hole near the bottom end of the said tilting beam, 20 an eye bolt attached to the mast below the said fixed collars and above the roller bearing collar a rope attached at one end to the clamp on the tilting beam, thence passed over the pulley in the mast, thence through 25 the hole in the tilting beam thence through the eye bolt, said tilting being adapted to be raised or lowered by means of said rope, a loading elevator, a pair of lifting booms pivotally secured at their lower ends to the

said elevator, at their upper ends to the 30 lower fixed collar, a double-tree swingingly secured by an eye bolt to the clamp on the tilting beam, a pair of pulleys attached to said double-tree, a pair of ropes attached to the extreme upper end of the tilting beam, 35 thence downward and around a pulley on each of the lifting booms, thence spliced so as to form one rope, a pulley attached to the lower end of said tilting beam, said rope passing through the said pulley, and a pulley 40 attached to the said base, said rope passing through said pulley.

6. In combination, a base, an upright mounted on the base, a bearing collar carried by the upright, in which the upright is 45 adapted to rotate, lifting booms pivotally secured to the upright, a locking rod fastened to the upright, and passing through a notch in the bearing collar, and means 50 for raising said rod when the booms are elevated to allow the rotation of the upright.

In witness whereof I hereunto set my hand this 17th day of May, 1911.

CANUTE H. MICKELSEN.
